UNITED STATES PATENT OFFICE.

ALBERT ANGELL, OF EAST ORANGE, NEW JERSEY, ASSIGNOR, BY DIRECT AND MESNE ASSIGNMENTS, TO MARCUS P. WARD AND ISAAC M. WILLIAMS, OF ORANGE, NEW JERSEY.

HEMP AND FLAX CLEANER.

SPECIFICATION forming part of Letters Patent No. 558,921, dated April 28, 1896.

Application filed August 15, 1895. Serial No. 559,349. (No model.)

To all whom it may concern:

Be it known that I, ALBERT ANGELL, a citizen of the United States, residing at East Orange, in the county of Essex and State of New Jersey, have invented certain new and useful Improvements in Hemp and Flax Cleaners, fully described and represented in the following specification and the accompanying drawings, forming a part of the same.

10 This invention relates to the production of cleaned hemp or flax fiber for the various purposes to which the same is applicable; and it consists, essentially, in a hemp and flax cleaner provided with a rotary reel and a blower with its nozzle adjacent to and directed along one side of the said reel.

In the annexed drawings, Figure 1 is an end elevation of the apparatus, showing the principal part of the gearing which connects the operative members. Fig. 2 is an elevation of the same, viewed from the delivery or front side. Fig. 3 is a plan of the same with a portion of the table broken away, and Fig. 4 is a sectional elevation taken on line $x-x$ in Fig. 2.

The machine, as illustrated herein, comprises a supporting-frame A, carrying a driving-shaft S, a pair of plain cylindrical feed-rollers $a-a$ adjacent thereto, a pair of interlocking blade-rollers $b-b$ adjacent to the feed-rollers, a cylindrical reel r , mounted upon an inclined shaft s beneath and slightly in advance of the blade-rollers, as indicated in Fig. 4, and a fan-blower B, with a nozzle B' directed along one side of and parallel with the reel, all of such operative members being connected together to rotate simultaneously, as hereinafter described.

The driving-shaft is provided upon one end with a large spur-gear c , meshing with the lower of two smaller intermeshing gears d upon the blade-roller shafts b' , such connection adapting them to rotate at a high rate of speed with relation to the driving-shaft, and the latter carries similarly at its opposite end a gear e , meshing with the lower of two intermeshing gears f upon the feed-roll shafts a' to rotate the feed-rolls at about the speed of the driving-shaft, which latter is provided, 50 in addition to the gears c and e , with a driv-

ing-pulley P for receiving the power for actuating the machine.

Upon the lower blade-roller shaft b' is fixed also a pulley g , which is connected by two belts h and m with the relatively small pulleys i and n , respectively, upon the inclined reel-shaft s and the blower-spindle for driving such members at a still greater velocity than the blade-rollers b .

The interlocking blade-rollers employed in the apparatus are of common form, comprising a pair of parallel cylinders formed each with a series of flat blades projected radially therefrom in intersecting paths, so as to bend the crushed stalks as they are fed between the same by the feed-rollers and scrape the woody matter from the fiber, and the reel r is of ordinary form, being shown in the drawings comprising two circular heads mounted upon a shaft s , inclined downwardly from the end adjacent to the blower with a series of peripheral bars parallel with the shaft for connecting such heads together.

In operation the machine is supplied with successive charges or bundles of hemp or flax stalks, each being first grasped and crushed by the feed-rollers and thence fed slowly forward between the rapidly-rotating blade-rollers which operate to scrape the woody portion previously loosened from the fiber and to propel the latter onward until it falls upon the more rapidly rotating reel.

As the rear ends of the crushed stalks are released by the feed-rollers, any rubbing action upon the forward ends of the fibers which may have previously taken place upon the reel during the retarded forward movement of the stalks ceases, and the bunch of fibers thus freed is then instantly seized by the reel and wound into a coil and then whirled thereon with great rapidity and simultaneously propelled by the air-blast from the blower B to the lower end of the reel, where it is permitted to drop off upon the reel-shaft into a position which is readily accessible for its removal by an attendant. The final whirling of the coil of partially-cleaned fibers by its greater centrifugal action upon such fibers as remain weighted with the partially-loosened foreign particles causes such fibers to fly out.

- ward to the periphery of the coil, where the impingement thereon of the air-blast, with the preferable assistance of the abrasive action of the adjacent sides of the frame or other suitable abutment, operate to brush off such foreign particles, leaving the whole coil entirely free from the woody substance of the stalk which may have adhered through the previous crushing and scraping operations.
- 10 While I have illustrated the reel herein as mounted upon an inclined shaft in order to assist the blower in the propulsion of the successive coils of fiber collected thereon to its lower end by gravitation, it is obvious that 15 the force of the blast may be so regulated as to obviate the necessity or desirability of such inclination of the reel, in which case the reel and adjacent nozzle of the blower would be horizontal.
- 20 It will also be observed that the precise design of the frame of the machine and the means of driving the operative members illustrated herein are unessential to the present 25 invention, which relates to the combination and arrangement of the operative members of the machine herein shown and described.
- Although the reel is shown herein of cylindrical form, it may be found preferable in some instances to make it of conical form
- 30 with the peripheral bars converging toward the lower end, in order to increase the freedom of movement of the coils of fiber along the reel as they approach the lower end.

Having thus set forth the nature of the in-

vention, what I claim herein, and desire to 35 secure by Letters Patent, is—

1. A hemp and flax cleaner provided with a rotary reel and a blower with nozzle adjacent to and directed along one side of the said reel, as and for the purpose set forth. 40

2. In a hemp and flax cleaner, the combination, with a pair of feed-rollers and an adjacent pair of interlocking blade-rollers, of an adjacent rotary reel arranged below the level of the said interlocking blade-rollers, a 45 blower with nozzle adjacent to one end of the said reel and directed along one side of the same, and means for actuating the said members of the machine, as and for the purpose set forth. 50

3. In a hemp and flax cleaner, the combination, with a pair of feed-rollers and an adjacent pair of interlocking blade-rollers, of an adjacent rotary reel mounted upon an inclined shaft arranged below the level of the 55 said blade-rollers, a blower adjacent to the upper end of the said reel with its nozzle directed along one side of the same, and means for actuating the said members of the machine, as and for the purpose set forth. 60

In testimony whereof I have hereunto set my hand in the presence of two subscribing witnesses.

ALBERT ANGELL.
